UNITED STATES PATENT OFFICE.

GEORGE H. JONES, OF OREGON, ILLINOIS.

SOUND BOARD FOR PIANOS.

Application filed September 30, 1922. Serial No. 591,619.

My invention relates to improvements in sound boards for pianos and has for its object the provision of an improved piano construction by means of which the tone or 5 the quality of the tone thereof is greatly improved and the resonance thereof increased.

Other objects will appear hereinafter.

The invention consists in the combinations and arrangements of parts hereinafter described and claimed.

The invention will be best understood by reference to the accompanying drawings forming a part of this specification, and in 15 which,

Fig. 1, is a rear view of a piano embodying the invention, and

Fig. 2, is a partial section taken on line 2—2 of Fig. 1.

20 The preferred form of construction as illustrated in the drawings comprises an ordinary upright piano body or casing 3, with the usual sound board 4 and having the usual treble bridge 5 and bass bridge 25 6, mounted thereon in the usual way to support the strings thereof in the usual way. The sound board 4 is provided with the usual ribs 7 on its back and the usual vertical posts 8 and 9 provided at the rear thereof

30 as shown. So much of the construction is old and well known and a usual one for the purpose and constitutes no part of my present invention excepting so far as the same is combined and cooperates with the novel 35 features of construction to be presently described.

In place of the usual vertical posts at the rear of the piano I provide two specially constructed posts 10 and 11, each consisting 40 of a solid post having incorporated therein and made a part thereof, a hollow violin body 12 of wood, as shown. Each violin body 12 is connected with the adjacent sound board 4 by means of a wooden tube or amplifying horn 13, each tube 13 being secured to and closed by the sound board opposite the treble bridge 5 and being also secured to and opening into the corresponding violin body 12. Each tube is provided with a bore 45 14, diverging from the sound board 4 to the corresponding violin body 12 and an opening 50 15 is provided in the body 12 to place the

interior thereof in open communication with the bore of the corresponding tube 13.

By this arrangement the tone or quality of the tone of the piano will be greatly amplified and rendered resonant and thus greatly improved in quality and musical effect. 55

While I have illustrated and described the preferred form of construction for carrying my invention into effect, this is capable of variation and modification without departing from the spirit of the invention. I, therefore, do not wish to be limited to the precise details of construction set forth, but 60 desire to avail myself of such variations and modifications as come within the scope of the appended claims. 65

Having described my invention, what I claim as new and desire to secure by Letters 70 Patent is:

1. The combination with an upright piano having a sound board and a vertical post traversing the back thereof adjacent the back of the sound board, of a hollow sound body 75 wider than and forming part of said post; and a sound tube secured to and having one end closed by said sound board, the other end of said tube being secured to and opening into said sound body, substantially as described. 80

2. The combination with a piano having a sound board, of a hollow sound body mounted adjacent said board; and a sound tube having one end secured to and closed by said sound board, the other end being secured to and opening into the said sound body, substantially as described. 85

3. The combination with an upright piano having a sound board, a treble bridge and a vertical post incorporated into the back thereof, said post being solid through the major portion of its length but having a hollow sound body wider than and forming a part of said post; of a sound tube having a divergent bore secured at the smaller end of its bore to said sound board opposite said treble bridge, the sound board closing the end of the tube, the other end of said tube being secured to and opening into said sound 95 body, substantially as described. 100

In testimony whereof I have signed my name to this specification.

GEORGE H. JONES.
